UNITED STATES PATENT OFFICE.

ANDREW JOHNSON, OF CRIPPLE CREEK, COLORADO.

RAIL BOND OR TIE.

1,211,162.

Patented Jan. 2, 1917.

Application filed August 19, 1916. Serial No. 115,824.

To all whom it may concern:

Be it known that I, ANDREW JOHNSON, a citizen of the United States, residing at Cripple Creek, in the county of Teller and State of Colorado, have invented a new and useful Rail Bond or Tie, of which the following is a specification.

The present invention relates to rail bonds, and has for its object the provision of a bond or tie which is of simple and strong construction, may be economically manufactured, and which securely holds the rails from spreading or turning over.

In carrying out the above object, the present invention provides three bars so formed and secured together as to hold the rails from spreading, and provides a telescopic relation between the three bars to brace the same against lateral strain and for firmly uniting them as a unit.

The invention will be best understood from a consideration of the following detailed description, taken in connection with the accompanying drawing forming part of this specification, with the further understanding that while the drawing shows a practical form of the invention, the latter is not confined to strict conformity with the showing of the drawing, but may be changed and modified so long as such changes and modifications come within the scope of the appended claims.

In the drawing: Figure 1 is a cross section through a pair of rails having the bond of this invention applied thereto, the bond being shown in side elevation and having one end in section. Fig. 2 is a transverse section through the rail bond, taken on the line 2—2 of Fig. 1, looking toward the inner side of the adjacent rail. Fig. 3 is a detail perspective view of the long bar or body member of the device. Fig. 4 is a detail perspective view of one of the short bars or connecting members of the device.

Referring to this drawing, 10 designates the rails of a track, which are spaced apart in the usual manner and are adapted to be held in place by the bond or tie of this invention.

The bond comprises a long bar or body member 11, which is substantially U-shaped in cross section, and which is placed in inverted position between the rails 10. The upper closed side of the body 11 has at its opposite ends longitudinally extending and upwardly offset lips 12 adapted to overlap

the inner base flanges of the rails, as clearly shown in Fig. 1. The closed side of the body member 11 lies substantially in the plane of the rail bases and forms a substantial brace for holding the rails 10 in spaced apart relation. Into each end of the body member 11 is telescoped a short solid bar 13, which projects outwardly beneath the rails 10 and is provided with inwardly overturned hooks forming lips 14 adapted for overlapping engagement with the outer base flanges of the rails 10. These bars 13 are adapted to slidably fit in the ends of the body bar 11, and are braced from lateral movement or vibration by the sides or flanges of the body bar 11. Bolts 15, or the like, are secured through the ends of the body member 11 and through the inner ends of the short bars 12 to secure the latter to the body bar and thus secure the rails 10 in place. The short bars 13 are preferably solid so as to reinforce the opposite ends of the bond immediately beneath and about the rails 10 and thus stand the strain at those points where the greatest pressure is exerted upon the bond, and to securely hold the rails from spreading or turning over. As the body bar 11 is open at its under side and projects below the plane of the rail bases, the bond of this invention when applied is anchored in the road bed and also serves as a tie to support the rails. The body or intermediate bar 11 may be of any suitable form having open ends to receive the end bars, and having side walls to retain the end bars in position and to accommodate the securing means for holding all of the bars together when applied to the rails.

What is claimed is:

1. A rail bond comprising an inverted channel bar formed in one piece adapted to be fitted between a pair of spaced rails, with its opposite ends bearing against the base flanges of said rails, and having offset lips at the tops of said ends engaging over said flanges, relatively short bars telescoping into each end of said channel bar and snugly fitting the same and projecting outwardly beneath the bases of said rails, means provided on the outer ends of said short bars for engagement with the outer base flanges of the rails, and means for securing the short bars in the channel bar.

2. A rail bond comprising an inverted channeled bar adapted to be fitted between a pair of spaced rails, and having longitu-

dinally extending lips at its opposite ends for engagement over the inner base flanges of the rails, a short solid bar telescoping into each end of the channeled bar and projecting outwardly beneath the bases of the rails and having inwardly overturned lips for engagement over the outer base flanges of the rails, and means for securing the short bars in the channeled bar.

- 10 3. A rail bond comprising a bar U-shaped in cross-section and adapted to be placed in inverted position between a pair of spaced rails, said U-shaped bar having on opposite ends and at its upper closed side 15 longitudinally projecting and upwardly offset lips adapted for engagement over the inner base flanges of the rails, short solid

bars telescoping into the opposite ends of the U-shaped bar and projecting outwardly therefrom beneath the rail bases, said short 20 bars having overturned lips on their outer ends for engagement over the outer base flanges of the rails, and securing means for holding the short bars in the ends of the long bar to prevent the rails from spreading 25 and turning over.

In testimony, that I claim the foregoing as my own, I have hereto affixed my signature in the presence of two witnesses.

ANDREW JOHNSON.
